UNITED STATES PATENT OFFICE.

HARRY COHN, OF BROOKLYN, NEW YORK, ASSIGNOR TO ROBERT FINDLAY MANUFACTURING CO., OF NEW YORK, N. Y., A CORPORATION OF NEW YORK.

DESIGN FOR A SEMI-INDIRECT-LIGHTING FIXTURE.

53,237.

Specification for Design.

Patented Apr. 29, 1919.

Application filed March 2, 1918. Serial No. 220,056. Term of patent 7 years.

To all whom it may concern:

Be it known that I, HARRY COHN, a citizen of the United States, residing at Brooklyn, in the county of Kings and State of New York, have invented a new, original, and ornamental Design for a Semi-Indirect Lighting Fixture, of which the following is a specification, reference being had to the accompanying drawing, forming part thereof.

The figure is a perspective view of a semi-indirect lighting fixture comprising the com-

bination of a canopy supporting a six-way hook, a plurality of chains suspended from said hook the said chains supporting an annular undercut member and a light reflecting bowl, and said bowl bearing the ornamental illustrations illustrated thereon, a tassel depending from the center of said bowl.

I claim:

The ornamental design for a semi-indirect lighting fixture, as shown and described.

HARRY COHN.
